CONSTANTINE CHRISTIAN FRANGOPOLU, OF SAN FRANCISCO, CALIFORNIA, ASSIGNEE
TO W. H. KENT, OF SAN FRANCISCO, CALIFORNIA.

DECARBONIZING-LIQUID INJECTOR AND AUXILIARY AIR CONTROL.

1,109,914.

Specification of Letters Patent.

Patented Sept. 8, 1914.

Application filed July 19, 1913. Serial No. 780,014.

To all whom it may concern:

Be it known that I, CONSTANTINE CHRISTIAN FRANGOPOLU, a citizen of the United States, residing in the city and county of San Francisco and State of California, have invented new and useful Improvements in Decarbonizing-Liquid Injectors and Auxiliary Air Control, of which the following is a specification.

10 This invention relates to a decarbonizing liquid injector and auxiliary air control.

The object of the invention is to provide a simple, easily operated device through which decarbonizing liquids may be admitted to the cylinders of a gas engine through the inlet manifold, while the engine is in motion.

15 A further object is to so construct the device that it may also be utilized as an auxiliary air control.

The invention consists of the parts and the construction and combination of parts as hereinafter more fully described and claimed, having reference to the accompanying drawings, in which—

Figure 1 is a perspective view of a car showing the application of the invention. Fig. 2 is a central vertical section of the container showing the position of the valve and pipe connections. Fig. 3 is an outside view of the container, partly broken away.

20 Referring to the drawings: A indicates the inlet manifold of a gas engine and B the dashboard of a car.

25 Suitably secured to the dashboard, as at 2, is a cylindrical-shaped contained 3, having a removable cover 4. Secured to the bottom of the container is a pipe 5, to the upper end of which is secured a valve 6, and connected to the opposite side of the valve and returning back to the bottom of the chamber is a pipe 7. The valve 5 is provided with an operating or adjusting lever 8, and the container 3 is slotted, as at 9, to permit the end 30 of the lever to project through the cylinder where it may be reached by the operator. The lower end of the pipe 5 is connected through a union 10 with a pipe 11, which in turn is connected with the manifold, as indicated at 12.

The position of the intake pipe, indicated at 12, together with the U-shaped connection mounted within the container, prevents any of the decarbonizing liquid from draining

down into the carbureter where it might mix with the gasolene or flood the same. It is only possible to drain the container when the engine is running, as a suction sufficient to lift the liquid through the U-shaped fitting is necessary before the liquid can escape from the container, and the suction is only obtained when the engine is running. Any possible interference with the carbureter is thus obviated.

In operation when the engine is running and when it is desired to admit a quantity of decarbonizing liquid, such as kerosene, to the cylinders, it is accomplished by first removing the cover 4. A suitable quantity of liquid is then poured into the container 3 and the cover replaced. The lever 8 is then turned to open the valve 6, which will immediately permit the suction of the manifold to draw the liquid out of the container, the time consumed in withdrawing the liquid being controlled by the position of the valve 6, which may be adjusted by the lever 8.

The decarbonizing liquid thus injected into the manifold is immediately conveyed to the several cylinders, through the inlet valves, where it is brought into contact with the carbon deposits within the cylinder.

I wish it understood that under normal running conditions it will not be necessary to carry any decarbonizing liquid within the container 3. It will therefore be seen that the container is normally empty and is only filled with a decarbonizing liquid when it is needed.

The piping connected with the manifold A, with connected valve 6 and container 3, may thus be used as an auxiliary air inlet, and the quantity of air admitted to the manifold may be controlled by adjusting the position of the valve 6; air being permitted to enter through the slot 9 and pipe 7; the pipe 7 being sufficiently removed from the bottom to permit the admission of air, which being drawn directly from the atmosphere and not being previously affected by the heat of the engine before entering the container 3, has a tendency to cool the cylinders.

A simple, compact, easily operated and adjustable device is thus provided for injecting decarbonizing liquids into the cylinders and which may also be utilized as an

auxiliary air control; thus its utility is doubled and the best efficiency and operation of the engine is obtained.

Having thus described my invention, what 5 I claim and desire to secure by Letters Patent, is:

1. In combination with a gas engine manifold, a receptacle; a U-shaped pipe mounted in said receptacle and connected to said 10 manifold, a valve in said pipe, means to operate said valve, said receptacle having a slot through which said means extends to allow the latter to move in said slot so as to enable opening and closing of the valve, 15 said slot also acting as an inlet for air to enable the latter to enter the receptacle and be drawn through said pipe to enter the manifold, and a cover for the receptacle.

2. In combination with a gas engine manifold, a receptacle, a U-shaped pipe mounted 20

in said receptacle and connected to said manifold, a valve in said pipe, means to operate said valve, said receptacle having a slot, which is located in one side thereof and through which said means extends to 25 enable the means to be moved along the length of the slot to enable opening and closing of the valve, said slot also acting as an inlet for air to enable the latter to enter the receptacle and be drawn through said 30 pipe to enter the manifold, and a cover for the receptacle.

In testimony whereof I have hereunto set my hand in the presence of two subscribing witnesses.

CONSTANTINE CHRISTIAN FRANGOPOLU.
